UNITED STATES PATENT OFFICE

JOSEPH ROBINSON, OF NEW YORK, N. Y.

AUTOMATIC TRAIN-PIPE COUPLING

Application filed May 15, 1923, Serial No. 639,222. Renewed February 21, 1930.

My invention relates to automatic train pipe couplings and has among its objects to provide an improved means for reducing the retroaction on the supporting spring of the pressure of the fluid carried in the coupling head, whereby the head is supported with the minimum resistance to longitudinal and lateral movement in all the positions it assumes in service. This object is attained by providing the coupling head with a pair of guides lying one in advance of the other and on opposite sides of the longitudinal axis of the head, the guides being joined by a substantially flat portion which extends diagonally from one guide to the other and constitutes the coupling face of the head. Extending through this portion I provide a conduit to contain the aforesaid fluid, the longitudinal axis of the conduit being arranged diagonally to the longitudinal axis of the head. In this manner the backward pressure of the fluid is divided between the guides of mated coupling heads and the supporting spring thereof, and the tendency of the heads to separate or "open up" under such pressure is minimized. Among the important advantages resulting from this arrangement is that it permits of the use of a much lighter supporting spring than has been possible heretofore with coupling heads which do not have some means for positively locking them together. In the present construction the spring need have only the resistance necessary to project the head forward into the proper horizontal coupling position, and hence it may be made much lighter and shorter than in the case of previous constructions and yet allow of the required compressional travel to accommodate the relative movement between the cars. Shortening the spring materially reduces the overhang of the coupling head with reference to the bracket and permits the use of a bracket which is practically straight vertically. By reducing the length and size of the supporting spring the rod which ties the coupling head to the bracket may also be reduced, thus permitting the use of a more compact universal joint which, in conjunction with the relatively low resistance of the supporting spring, materially reduces the resistance to lateral movement of the coupling head under the sharp whipping movement of running cars. In most previous constructions, and differing in this respect from the present one, the rod mentioned is relied upon to prevent undue rotation of the coupling head about its longitudinal axis, which arrangement requires the use of a much larger rod, and hence a much larger universal joint, than I employ.

To maintain the coupling head of previous connectors in the normal coupling position, a flange is usually employed to contact with the rear face of the bracket, which construction requires that the supporting spring be under considerable initial compression in order to draw the flange against the bracket with the several hundred pounds force required to properly sustain the head. Inasmuch as this force is transmitted to the bracket immediately opposing coupling heads connect, it results—when added to the further compression of the spring occurring in the act of coupling—in overloading the bracket. In consequence the several parts of the connector, and especially the bolts which secure the bracket to the car coupler, are placed under excessively high stresses. In addition to this the high resistance of the supporting spring keeps the inner faces of the car coupler knuckles in contact under many conditions wherein they would otherwise be constantly breaking contact, or be only lightly contacting, and this results in excessive wear on the knuckles—a very objectionable feature. Likewise this heavy spring resistance frequently interferes with the coupling of the cars, especially if the standing car be empty and on a slight down grade, or on level track, with the brakes not set. Under such conditions the car is frequently pushed along the track unless the oncoming car approaches it at an objectionable rate of speed.

My invention, and the further objects thereof, are fully described in the following specification, pointed out in the appended claims, and illustrated in the accompanying drawings in which:

Figure 1 is a side elevation of my improved

train pipe coupling with the usual train pipe hose 29 and the nipple 11 omitted.

Figure 2 is a rear view of the coupling head taken on the line 2—2 of Figure 1.

Figure 3 is a horizontal sectional view through my improvement, showing it coupled to a complementary coupling head.

Figure 4, is a front view of the bracket taken on the line 4—4 of Figure 1.

My improved coupling head A comprises a pair of guides 5 and 6 which may be either of the form shown or such as is illustrated in my co-pending application Serial 537,827, filed February 20, 1922, or of other suitable design. The guides are arranged one in front of the other and on opposite sides of the longitudinal axis of the coupling head A, one of the guides being hollow or ring shaped to receive the other, as shown in Figure 3. The front face of one of the guides and the base of the other are joined by a substantially flat portion 7 which extends diagonally between the guides, and is preferably formed integral therewith and constitutes the coupling face of the head A. In this portion an opening or aperture 8 is formed and within this aperture I suitably mount, as by a bayonet joint comprising interlocking lugs 9 and 10, shown in Figure 3, a suitable conduit or fitting 11. The longitudinal axis of the conduit extends at about a 45° angle, to the longitudinal axis of the head, both of which axes, and preferably the longitudinal axis of the supporting spring B also—intersect at substantially the center of this portion and in approximately the plane of the front face thereof. This arrangement, in addition to having the advantages heretofore ascribed to it, provides a straight unobstructed course for the air through the connectors, and eliminates all impediments therein to the quick flow of the air—a very important consideration in its bearing upon the efficient operation of the air brakes.

In the forward end of the conduit 11, or otherwise disposed in the aperture 8, I mount a resilient gasket 12 which projects slightly beyond the coupling face of the head A, and is adapted to abut a complementary gasket in a counterpart head or coupling. The gasket is provided with a groove 14 which the air enters to force the mating gaskets into firm contact one with the other. The construction gives to mated gaskets a piston action which serves not only to force them into tight engagement, but also to shift, or force, the guides of mated coupling heads A laterally into tight engagement. That is to say, under the pressure of the fluid carried by guide 5 of mated heads will be forced into tight engagement with the guide or ring 6 of such heads at the point 15, illustrated particularly in Figure 3. This produces an interlock between mated heads, and that it may

be most effective it is preferable that the taper of the mating guides at the surfaces 15 be not too abrupt. For the purpose of strengthening the head A I provide it at the top and bottom with rearwardly extending ribs 16 which merge into an annular seat 17 formed on the rear side of the head, the conduit 11 being positioned between these ribs.

To yieldingly support the coupling head from the car I provide a suitable bracket C, attached to the usual car coupler as by means of a suitable lug D and bolts 18. The lower end of the bracket is open, as shown in Figures 3 and 4, and is provided with a concave semi-spherical seat or bearing 19 on its front face to receive a complementary pivot device or plate 20 the rear face of which is convex and semi-spherical in form and is mounted on the seat 19 for rocking or universal movement thereon. The pivot device is provided with seat 21 to receive the buffer or supporting spring B. A stem or rod 22 is suitably secured to the coupling head A, preferably as by threads as shown in Figure 3, and extends rearwardly of the head through the pivot device 20 and the seat 19 of the bracket. The pivot device is provided with an elongated shank 23 to afford a large bearing therein for the rod that the rod may efficiently rock the pivot device when the coupling head moves to accommodate the movements of the car. The buffer spring B is interposed between the bracket C and the coupling head A, and surrounds the rod 22 and rests at one end upon the seat 17 and at the other end upon the seat 21. The rod or stem 22 is round in cross section and of relatively small diameter which, taken with the relatively small diameter of the spring B, permits of the use of a compact universal joint, formed by the device 21 and the bearing 19, which permits universal movement to the coupling head A with the minimum of resistance.

A suitable nut 24 is adjustably mounted upon the rear end of the rod 22 and serves to tie the coupling head to the bracket and to maintain the buffer spring B under sufficient compression to insure the head being moved to the proper coupling position, shown in Figure 1, upon uncoupling of the cars.

To adjustably support the head against downward movement and to prevent rotation thereof, I provide a suitable rod or member 25 connected in any desired manner to the head A, preferably pivotally connected thereto as by means of a lug 26, formed integral with the head, and a pin 27 which passes through the lug and the rod—the fit between these last named parts being comparatively tight. The upper end of the rod passes loosely through an opening formed in the bracket at a point considerably above the pivot device 20 and threadingly receives a nut 28, by which the rod may be adjusted to

raise or lower the head A to the most efficient coupling position.

When it is desired to remove a defective gasket 12 from between the faces of mated coupling heads constructed according to my improvement, it is necessary merely to rotate the fitting 11 one quarter turn to the right or left against the torsional resistance of the usual rubber train pipe hose 29, shown in Figure 1, whereupon the fitting and the gasket may be extracted rearwardly from the head and renewed and replaced at will. The hose 29 is preferably clamped directly to the shank 30 of the conduit 11 in the usual manner, the torsional resistance of the hose serving to maintain the conduit in its interlocked position in the coupling head A.

The simplicity and reduced weight of the several parts of my improvement, and the use of a relatively small buffer spring B, effect a material saving in the cost manufacture which renders the construction more accessible to the trade.

What I claim is:

1. In an automatic train pipe connector, in combination, a coupling head having a front guide and a rear guide integral therewith and arranged on opposite sides of the general longitudinal axis of the head, the base of each of said guides being arranged substantially at right angles to the longitudinal axis of the head, said head having a diagonal portion extending between said guides and across the longitudinal axis of the head, said diagonal portion having an opening therein, a conduit mounted in said opening and removable rearwardly therefrom, a stem adjustably connected to said head with the axis thereof substantially in line with the center of said opening, a bracket, means for supporting the rear end of said stem on said bracket and a rod pivotally connected to said head and extending rearwardly and upwardly therefrom and engaging said bracket above said stem.

2. In an automatic train pipe connector, in combination, a coupling head having a front guide and a rear guide integral therewith and arranged on opposite sides of the general longitudinal axis of the head, the base of each of said guides being arranged substantially at right angles to the longitudinal axis of the head, said head having a diagonal portion extending between said guides and across the longitudinal axis of the head, said diagonal portion having an opening therein, a conduit mounted in said opening and removable rearwardly therefrom, a stem adjustably connected to said head with the axis thereof substantially in line with the center of said opening, a bracket, means for supporting the rear end of said stem on said bracket and a rod pivotally connected to said head and extending rearwardly and upwardly therefrom and

means adjustably mounted on said rod and engaging said bracket above said stem.

3. In an automatic train pipe connector, in combination, a coupling head having a front guide with the base thereof arranged substantially at right angles to the longitudinal axis of the head and a rear guide also having its base arranged substantially at right angles to the longitudinal axis of the head, said head also having a portion arranged between said guides and extending diagonally of the longitudinal axis of the head, the front face of said portion constituting the coupling face of said head, said portion having an opening therethrough, a conduit mounted in said opening, means for removably securing said conduit in said opening whereby the same may be removed rearwardly from said opening while said head is coupled to a mating head, a stem adjustably connected to said head and projecting rearwardly therefrom with its axis substantially in line with the center of said opening.

In testimony whereof I hereunto affix my signature.

JOSEPH ROBINSON.
